UNITED STATES PATENT OFFICE.

MELROSE G. KOPE, OF DAYTON, OHIO, ASSIGNOR TO THE RALKO PRODUCTS COMPANY, OF DAYTON, OHIO, A CORPORATION OF OHIO.

PORTABLE FIRE-EXTINGUISHER.

1,317,507.

Specification of Letters Patent. Patented Sept. 30, 1919.

Application filed November 1, 1917. Serial No. 199,622.

To all whom it may concern:

- Be it known that I, MELROSE G. KOPE, a citizen of the United States, residing at Dayton, in the county of Montgomery and 5 State of Ohio, have invented certain new and useful Improvements in Portable Fire-Extinguishers, of which the following is a specification, reference being had therein to the accompanying drawing.
- 10 This invention relates to portable fire extinguishers, and more particularly to that class of fire extinguishers in which the casing, or body portion, is grasped in the hand of the operator while the liquid is being 15 discharged therefrom.
- In fire extinguishers of this type now on the market, for the most part at least, the liquid is discharged from the casing or container by means of pumping mechanism consisting of a cylinder and a piston mounted within the casing and which must be manipulated by the operator. This construction is open to several serious objections, among which are the following: The piston 20 and its cylinder being constantly submerged in the fire extinguishing liquid within the container are subjected to the corrosive action of the chemical elements of the liquid which not infrequently causes the piston to 25 stick or "freeze" to the walls of the cylinder, thus interfering with the proper operation of the device and sometimes rendering it wholly inoperative; it is very difficult to 30 grasp the casing with one hand and hold 35 the same steady while operating the pump with the other hand, hence it is almost impossible to direct the stream of liquid accurately upon the fire; the pumping mechanism occupies a considerable space within 40 the casing and it is necessary that the casing should be made correspondingly larger in order that it may contain the necessary amount of liquid; and further the mechanism 45 is expensive to manufacture and the fire extinguisher is correspondingly high priced, thus making it impractical to substitute a plurality of extinguishers of smaller size, which could be more conveniently handled, for a single large container.
- 50 In certain makes of fire extinguishers of this type provision is made for the storing of a small quantity of air in the casing by the action of the pumping mechanism. While this enables the liquid to be discharged more continuously from the casing 55
- it does not eliminate the pumping operation and therefore does not prevent the wobbling of the casing and of the stream of liquid.
- The object of the present invention is to provide a fire extinguisher of this type 60 which will be free from the faults above enumerated; and to this end it is a further object of the invention to provide a device of this kind from which the liquid will be discharged in a continuous stream without 65 action on the part of the operator other than that required to set the mechanism in operation, thus enabling the stream of liquid to be directed accurately upon the fire.
- It is also an object of the invention to so 70 construct and arrange the mechanism that when the extinguisher is in its normal, idle position the operating mechanism will not be in contact with the liquid within the container and will therefore not be subjected 75 to the chemical action thereof.
- It is also an object of the invention to so 80 construct and arrange the mechanism that a small-sized casing will contain a relatively large amount of liquid, thus enabling the device to be made in small sizes, which are not only more convenient to handle, but are less expensive.
- It is also an object of the invention to 85 provide an exteriorly arranged controlling device for the mechanism which discharges the liquid, which device will be of such a character that it can be quickly and easily operated to release the mechanism for operation, and will be compactly arranged 90 when the extinguisher is idle.
- It is also an object of the invention to 95 provide means for controlling the stream of liquid which is discharged from the casing; and to combine with this controlling device a stopper which can be removed to permit the casing to be refilled.
- It is a further object of the invention to 100 provide in combination with such a fire extinguisher, a supporting device which will serve to automatically release the liquid discharging device within the casing and thus render the extinguisher operative so that it will require only the opening of the discharge valve to render the device as a whole 105 operative. Other objects of the invention will appear as the device is described in detail.
- In the accompanying drawings Figure 1 110 is a front elevation of a fire extinguisher

embodying my invention; Fig. 2 is a vertical sectional view taken on the line 2—2 of Fig. 1; Fig. 3 is a detail view of a portion of the extinguisher showing the releasing device for the operating mechanism; Fig. 4 is a sectional view taken on the line 4—4 of Fig. 3; Fig. 5 is a front elevation, partially broken away, showing the supporting and releasing devices; and Fig. 6 is a detail view of the nozzle member.

In these drawings I have illustrated one embodiment of my invention and have shown the same as comprising a casing having a cylindrical body portion 5 closed at its ends by cup-shaped cylinder heads 6 and 7. The casing may be of any suitable material, such as cast iron, steel, or glass. The character of the chemicals stored in the casing will naturally have a bearing upon the character of material employed in its construction. As shown in Figs. 1 and 2 the cylinder and the lower cylinder head 6 are cast in a single piece and the upper cylinder head 7 is detachably secured thereto, in the present instance, by providing the cylinder head 7 with a screw-threaded flange 8 to engage corresponding threads in the upper end of the cylinder 5. The lower cylinder head 6 is provided with a discharge opening and, in the present construction, has a downwardly extending boss, or neck, 9, which is screw-threaded to receive a stopper 10 having at its outer end a head, or flange, 11, by means of which it may be manipulated. This stopper is hollow but is closed at its inner end by a wall 12 having therein a small port, or opening, 13, which constitutes the discharge opening for the casing, or container. This port is controlled by means of a valve 14 which is connected with, and preferably formed integral with, a nozzle 15 which is screw-threaded into the hollow stopper 10 and has a longitudinally extending passageway, or discharge opening, 16, which is bifurcated at its inner end to bridge the valve member 14. This nozzle is also provided with a milled nut, or head, 17, by means of which it may be manipulated to adjust the valve 14 and thus open or close the discharge opening, or to adjust the valve to regulate the size of the stream which is discharged. Preferably the milled nut 17 has an inwardly extending flange 19 which, when the valve 14 is seated, incloses the milled head 11 on the stopper so that the nut 17 alone is visible. This not only improves the appearance of the device but it presents to the operator a single device to be operated, thus making it impossible for the operator, in the excitement incident to a fire, to attempt to operate the wrong part.

The liquid is discharged from the container automatically, the discharge mechanism being normally locked in an inoper-

ative position and being released only when it is desired to use the fire extinguisher. As here shown this mechanism consists of a spring actuated piston 20 mounted in the cylinder 5. As here shown the piston is an ordinary solid piston and is provided with a piston ring 21 to insure a tight fit with the wall of the cylinder. A spring 22 is confined between the piston 20 and the upper cylinder head 7 and serves, when the piston is released, to move the piston toward the lower end of the cylinder and discharge the liquid therefrom through the port 13. The spring may be of any suitable character but is here shown as of a type which may be compressed into a very small compact form and thus will occupy but little room within the cylinder when the piston is in its idle position. Suitable means are arranged exteriorly of the casing for controlling the operation of the piston. As here shown a retracting device is connected with the piston and extends through an opening 23 in the upper cylinder head 7, thus enabling the piston to be withdrawn to its idle position, against the tension of the spring, and permitting it to be moved downwardly by the spring when released. Preferably this retracting device is foldable that it may be positioned close to the casing when not in use, and in the present instance it is shown as a flexible cord, or wire cable, 24, which is rigidly secured at its inner end to the piston and may be folded about the outer surface of the cylinder head 7 and carried downwardly along the side of the casing. The cord is provided with a handle 25 to enable it to be easily operated, and this handle also serves as a locking device. To this end the handle co-operates with a pair of lugs 26 projecting from the casing near the lower end thereof and spaced apart to receive the cord 24 between them. When the cord has been placed between the lugs the handle will engage the lugs and will be held in contact therewith by the action on the spring of the piston. To release the piston it is only necessary to move the handle outwardly to withdraw the cord from between the lugs. It is desirable that the cylinder head should be so constructed that no sharp turns will be imparted to the cord when the same is bent about the outer surface thereof. To this end the cylinder head is provided with a thickened portion, or rib, 27 having a long curve at its upper end, adjacent to the opening 3 in the cylinder head, and tapered downwardly until it merges into the outer surface of the cylinder head near the lower edge thereof. The structure is provided with suitable means for supporting the same in an upright position, such as a lip, or plate, 28, provided with a key hole slot 29, which plate is in the present instance formed integral with

the upper cylinder head 7 and extends upwardly in line with the adjacent portion of the cylinder 5. When this supporting plate has been placed in engagement with a stud 5 or screw in the wall where it is desired to support the fire extinguisher, the device will hang with the discharge nozzle downward and with the piston and its spring at the upper end of the casing where they will be 10 out of contact with the liquid in the casing. Consequently there is no opportunity for the liquid to act upon the piston or to leak past the piston so as to act upon the spring or other parts of the mechanism, or to 15 escape from the casing. As the piston is not relied upon to retain the liquid within the container when the latter is in its normal, idle position it is not necessary that the fit of the piston within the cylinder be 20 so tight as to prevent leakage. When it is desired to use the extinguisher it is removed from the wall, the handle 25 moved out of engagement with the lugs and released. As soon as the nozzle has been brought to play 25 upon the fire it is rotated to unseat the valve 13 and permit the liquid to be discharged in a continuous stream, the size of which may be regulated by adjusting the valve. The action of the spring upon the piston not only 30 produces a continuous stream but serves to operate the piston until the liquid is entirely discharged without any further action whatever on the part of the operator, thus allowing him to give his whole attention to the 35 directing of the stream upon the fire. When the container has been emptied and it is desired to refill the same the piston is moved to its uppermost, or idle position, and locked in this position. The combined stopper and 40 nozzle are then removed and the container again filled with the fire extinguishing liquid, after which the combined stopper and nozzle are replaced and the valve closed. There is no pressure whatever on 45 the liquid when the device is idle and the pressure at no time is excessive, consequently the casing may be made of relatively light material, which not only renders the same less expensive, but reduces its size and 50 weight, and thus makes it more convenient to handle.

If desired there may be provided in connection with the supporting device, or plate, 28, a device which will automatically release 55 the piston, by disengaging the handle from the lugs, as the device is removed from the wall. To this end I have provided a pair of arms 30 which project outwardly from the wall about the neck of the container, at 60 the lower end thereof, and are provided at their outer ends with hook-shaped portions 31 which engage the handle. As the container is usually hung in an elevated position it will be apparent that in removing 65 the same from the wall it is first moved up-

wardly to permit the plate 28 to be removed from the supporting screw and the upper portion thereof will then be moved downwardly, the device as a whole turning about the point of contact of the handle with the 70 hook-shaped portions 34 of the arms 30. When the container has been turned end for end to bring the discharge end uppermost, the hooks will extend between the handle and the end of the container, and consequently as the discharge end of the device 75 passes the hooks its outward movement will serve to withdraw the handle from the lugs and thus release the piston. The casing may be made either partly or wholly of glass and, 80 as shown in Fig. 5, I have made the cylinder of the casing of glass, as this material is not only impervious to the chemical action of the liquids, but also enables the amount of liquid in the container to be readily determined. 85

While I have shown and described one embodiment of my invention I wish it to be understood that I do not desire to be limited to the details of construction as various modifications will occur to a person skilled in the art. 90

Having now fully described my invention, what I claim as new and desire to secure by Letters Patent, is:— 95

1. In a fire extinguisher, a casing adapted to be grasped by the hand of the operator during the discharge of the liquid therefrom and having a discharge opening, a piston mounted in said casing, a spring arranged between said piston and one end of said casing to act on said piston, a retracting device connected with said piston, extending through the end of said casing and having that portion thereof which extends 100 beyond said casing when said piston is in its retracted position flexible to permit the same to be folded into a position alongside of said casing, and means arranged externally of said casing to coöperate with said 105 retracting device to retain said piston in its retracted position. 110

2. In a fire extinguisher comprising a casing adapted to be grasped by the hand of the operator during the discharge of the 115 liquid therefrom and having a discharge opening, a piston mounted in said casing, a spring arranged between said piston and the end of said casing to act on said piston, a flexible retracting device connected with 120 said piston and extending through the end of said casing, and means secured to one side of said casing and coöperating with said flexible member to retain said piston in its retracted position. 125

3. In a fire extinguisher comprising a casing adapted to be grasped by the hand of the operator during the discharge of the liquid therefrom and having a discharge opening, a piston mounted in said casing, a 130

4
spring arranged between said piston and the end of said casing to act on said piston, a flexible retracting member connected with said piston and extending through the end 5 of said casing, a handle secured to said flexible member, and a device secured to said casing to engage said handle and retain said piston in its retracted position.

4. In a fire extinguisher comprising a 10 casing adapted to be grasped in the hand of the operator during the discharge of the liquid therefrom and having a discharge opening, a piston mounted in said casing, a spring arranged between the end of said casing and said piston to act on the latter, a flexible retracting device connected with said piston and extending through the end 15 of said casing, a handle secured to said flexible device, and parts projecting from 20 said casing near the discharge end thereof to engage said handle and retain said piston in its retracted position.

5. In a fire extinguisher, a casing having an opening in one end thereof, a boss 25 surrounding said opening, a stopper screw-threaded into said boss and having a discharge opening communicating with the interior of said casing and also having a head by means of which it may be manipulated, 30 a nozzle having a portion screw-threaded into said stopper and having a nut by means of which it may be rotated, said nut having a flange arranged to inclose the head on said stopper when the nozzle is in its inner- 35 most position, said nozzle also having a passageway communicating with said discharge opening, a valve connected with said nozzle and adapted to open and close said discharge opening, a piston mounted in said 40 casing, and means to actuate said piston to force the contents of said casing through said discharge opening.

6. In a fire extinguisher, a casing having an opening in one end thereof, a boss sur- 45 rounding said opening, a stopper screw-threaded into said boss and having a discharge opening communicating with the interior of said casing and also having a head by means of which it may be manipulated, 50 a nozzle having a portion screw-threaded into said stopper and having a nut by means of which it may be rotated, said nozzle also having a passageway communicating with said discharge opening, a valve connected 55 with said nozzle and adapted to open and close said discharge opening, a piston mounted in said casing, a spring confined between said piston and the end of said casing to act on the piston to cause the contents of the casing to be discharged through 60 said opening, a flexible retracting member connected with said piston, and a part carried by said casing and co-operating with

said actuating member to retain the piston in its retracted position.

7. In a fire extinguisher comprising a 65 casing adapted to be grasped by the hand of the operator during the discharge of the liquid therefrom and having a discharge opening at one end thereof, means to close 70 said opening, a piston mounted in said casing, a spring acting on said piston to move the same toward said discharge opening, a flexible member connected with said piston and extending through that end of said cas- 75 ing opposite said discharge opening, a handle connected with said flexible member, parts projecting from the side of said casing to engage said handle and retain said piston in its uppermost position, a supporting de- 80 vice secured to that side of said casing opposite said projecting parts, and a device adapted to be mounted on a fixed support near said casing and having parts extending transversely of said casing and provided 85 with hook-shaped portions to engage said handle.

8. In a fire extinguisher comprising a 90 casing adapted to be grasped by the hand of the operator during the discharge of the liquid therefrom and having a discharge opening at one end thereof, means to close 95 said opening, a piston mounted in said casing, a spring acting on said piston to move the same toward said discharge opening, a flexible member connected with said piston and extending through that end of said cas- 100 ing opposite said discharge opening, a handle connected with said flexible member, means carried by said casing to engage said handle to retain the piston in its uppermost position, a supporting device for said casing, and a device adapted to be mounted on a fixed support to engage said handle and disengage the same from said engaging 105 means when said casing is removed from said supporting device, thereby releasing said piston.

9. In a fire extinguisher comprising a 110 casing having a discharge opening at one end thereof and adapted to be grasped in the hand of the operator during the discharge of the liquid therefrom, mechanism mounted within said casing to discharge the liquid through said opening, means for re- 115 taining said mechanism normally in an in-operative position, a supporting device for said casing, and a device adapted to be mounted on a fixed support and co-operating with said supporting device to release 120 the mechanism within said casing from said retaining means when said casing is removed from said supporting device.

In testimony whereof I affix my signature hereto.

MELROSE G. KOPF.
